J. ROMEYN

FUEL PUMP FOR INTERNAL COMBUSTION ENGINES

Filed Nov. 27, 1923

FIG. 2.

FIG. 3.

Inventor:

Jean Romeyn

By *John Daniels, Jr.*

Attorney.

UNITED STATES PATENT OFFICE.

JEAN ROMEYN, OF BRUSSELS, BELGIUM.

FUEL PUMP FOR INTERNAL-COMBUSTION ENGINES.

Application filed November 27, 1923. Serial No. 677,337.

To all whom it may concern:

Be it known that I, JEAN ROMEYN, a citizen of the Kingdom of Netherlands, and resident of Brussels, Belgium, have invented 5 certain new and useful Improvements in or Relating to Fuel Pumps for Internal-Combustion Engines; and I do hereby declare the following to be a full, clear, and exact description of the invention, such as will 10 enable others skilled in the art to which it appertains to make and use the same, reference being had to the accompanying drawings, and to letters or figures of reference marked therein, which form a part of this 15 specification.

The present invention relates to fuel pumps for internal combustion engines in which the action of the centrifugal governor is transmitted to the pump through a shaft, 20 which is turned through a certain angle according to the position of the governor.

In such a mechanism, especially when several pumps are regulated by a common shaft, it is important to arrange the shaft 25 so that the governor is able to move it without encountering any appreciable resistance.

The purpose of the present invention is to obtain, when running, the entire freedom of the regulating shaft.

According to the invention the regulating shaft is supported near the pump or near 30 each pump in a fixed bearing lined with a tubular fitting, which is loose both round the shaft and in the bearing, and receives from 35 any part of the pump oscillating movement.

In order that this invention may be readily understood, it is shown, by way of example in the accompanying drawings, in which,

Figure 1 is a vertical sectional view, with parts in elevation, of a fuel pump embodying the invention; Fig. 2 is a horizontal section on line 2—2, Fig. 1; and Fig. 3 is a side view of a detail of Fig. 2.

In the fuel pump represented by way of example in Fig. 1, and which, in the main, is of the ordinary type *a* is the body of the pump, and *b* is the plunger or piston fitted to slide therein and actuated from the shaft 45 *c* by means of the eccentric *d*, the rod *e* and the guide *f*; *g* is the suction valve, *h* the discharge valve, *i* a suction chamber into which the fuel is admitted through the pipe *j*, and *k* is the delivery pipe. The lever *l* is supported on the eccentric *m* keyed on the shaft 50 *n* and is oscillated by the rod *o* pivotally

connected to the guide *f*. *p* is a bearing in which the shaft *n* is supported, and *q* is a part which is fixed on a rod *r* attached by means of the connecting rod *s* to a point of the lever *l* and is so disposed as to keep the suction valve *g* open during part of the stroke of the piston *b*. The shaft *n* is not disposed in direct contact with the surface of the bearing *p* wherein it is mounted but, instead, passes loosely through a tubular liner *t* which is itself fitted loosely in said bearing. This liner is formed with a laterally-extending arm *u* which is forked at its free outer end to engage the pivot *v* that connects the upper end of rod *s* to the lever *l*; and since the latter is continuously rocked or oscillated, as above explained, the said forked arm *u* will likewise be oscillated, due to its connection therewith, with the result 70 that the liner *t* will be turned or rocked first in one direction and then in the other on the shaft *n* and in the bearing *p*.

Supposing the piston *b* is at its upper dead centre and starts its downwards stroke, 80 the suction valve *g* is opened. But as the part *q* moves downwards at the same time as the piston, after the latter has accomplished a part of its stroke, the valve *g* is closed and the fuel instead of flowing back through the valve *g* is forced through the valve *h* into the pipe *k*. In order to regulate the quantity of fuel delivered by the pump, it is sufficient to bring the point at 85 which the lever *l* is supported, that is the centre of the eccentric *m*, higher or lower. This may be effected by turning the shaft *n* through a certain angle, said shaft being connected to a centrifugal governor (not shown) to be operated automatically there- 90 by.

Supposing the shaft *n* occupies a given position and the speed increases, the governor opens and moves the shaft in the direction shown by the arrow. Under ordinary conditions the friction between the shaft *n* and the bearing *p* would have to be overcome, so that the movement of the governor would start only after the increase of speed has reached a value sufficient to produce an appreciable increase of the centrifugal forces. By supporting shaft *n* by the liner *t* which, as above explained, is constantly oscillated, the friction is periodically reversed and exerts only a slight alternative reaction upon the governor, so that when the latter is caused to move by a speed variation it en- 100 105 110

counters no additional resistance acting in a direction reverse to the direction in which the movement takes place, and hence it acts immediately.

- 5 The arrangement according to the invention is particularly useful when there are several pumps which are regulated by the same shaft, and the actuating eccentrics of which are set at equal angles around the 10 actuating shaft, because in this case, the defect to be eliminated is more pronounced (since the regulating shaft is supported in a series of bearings) and the reaction transmitted to the governor from the oscillating 15 liner sleeves (which are at a given moment in different periods of their movement) is practically negligible.

What I claim is:

1. In a fuel pump, the combination of a 20 reciprocatory piston; operating means therefor; a suction valve; a governor-controlled shaft for regulating the operation of said valve; a fixed bearing for said shaft, a tubular liner fitting loosely in said bearing and 25 loosely encircling said shaft; and means for continuously oscillating said liner relatively to said shaft and bearing to periodically reverse the direction of friction between the shaft and liner.
- 30 2. In a fuel pump, the combination of a reciprocatory piston; operating means therefor; a suction valve; a governor-controlled regulating shaft; a lever fulcrumed eccentrically on said shaft, whereby its fulcrum will be varied in conformity with the 35 movements of the shaft, said lever being connected with the piston-operating means to be continuously oscillated by the same; connections between said lever and valve to 40 operate the latter from the former; a fixed bearing for said shaft; and a tubular liner fitting loosely in said bearing and loosely encircling said shaft, said liner having a connection with said lever whereby it will

be continuously oscillated relatively to the 45 shaft and bearing and will periodically reverse the direction of friction between the shaft and liner.

3. In a fuel pump, the combination of a reciprocatory piston; operating means therefor; a suction valve; a governor-controlled regulating shaft; a lever fulcrumed eccentrically on said shaft, whereby its fulcrum will be varied in conformity with the movements of the shaft, said lever being connected with the piston-operating means to be continuously oscillated by the same; connections between said lever and valve to operate the latter from the former; a fixed bearing for said shaft; a tubular liner fitting loosely in said bearing and loosely encircling said shaft; and a forked arm on said liner connected with the lever to effect the continuous oscillation of the liner relative to the shaft and bearing, whereby the direction of friction between the liner and the shaft will be periodically reversed.

4. In a fuel pump, the combination of a reciprocatory piston; operating means therefor; a suction valve; a governor-controlled regulating shaft; a member mounted on said shaft to move therewith and connected to operate the valve; means for continuously oscillating said member; a fixed bearing for said shaft; and a tubular liner fitting loosely 75 in said bearing and loosely encircling said shaft, said liner being connected with said member to be continuously oscillated by the same relatively to the shaft and bearing and thereby periodically reverse the direction of 80 friction between said shaft and liner.

In testimony whereof I affix my signature in presence of two witnesses.

JEAN ROMEYN.
